UNITED STATES PATENT OFFICE.

HUGH A. ROBINSON, OF KEYPORT, NEW JERSEY.

AEROPLANE ATTACHMENT.

1,365,275.

Specification of Letters Patent. Patented Jan. 11, 1921.

Application filed June 4, 1919. Serial No. 301,677.

To all whom it may concern:

Be it known that I, HUGH A. ROBINSON, a citizen of the United States, residing at Keyport, in the county of Monmouth and State of New Jersey, have invented certain new and useful Improvements in Aeroplane Attachments, of which the following is a specification, reference being had therein to the accompanying drawing.

- 10 My invention relates to improvements in aeroplane attachments and more particularly has reference to a metal base or cradle for an engine adapted to be secured at the front of the fuselage of the aeroplane.
- 15 Referring to the accompanying drawings, Figure 1 illustrates in perspective a suitable form of metal base or cradle for an engine bed embodying an application of my invention. Fig. 2 is an enlarged perspective view
- 20 partly broken away illustrating the method of connecting the same to the end of the longérons, and Fig. 3 is a front view looking from left to right at Fig. 1.

Referring now more particularly to Fig. 2, it will be observed that the end of the longeron is secured within the socket member 4 where it is securely clamped by bolts passing through the holes 5 in the lugs 6. 7 indicates other holes through which bolts are passed for securing the ends of the longeron, and 8 indicates a bolt projecting through the plate 9 secured to the end of the longeron as shown and said bolt is provided with a nut 10 for securing the socket 4 to the longeron, said socket then being secured to the engine bed or cradle. The bottom of the engine bed or cradle may be secured by lugs such as 11 provided with bolt holes 12.

18 indicates the side members of the cradle forming the bed or support for the engine the lugs of which are secured through the bolt holes 14, and 15, 16, 15', 16' indicate the side bracing members. 17, 18, 19, and 17', 18' and 19' indicate the inwardly projecting bracing members of the frame for supporting the bed or parallel members 13. 20—21

indicate the uprights at the back of the cradle or frame and the front of these are preferably covered by a screen or plate 22 which extends entirely across to prevent back flashing and to protect the aviator. The spacer bar 23 serves to connect the front ends of the engine bed 13 and the lugs 24 serve as anchorages for the stay wires or other supporting means employed.

The engine cradle or frame support shown, it will be observed provides a strong, light and rigid structure and may be conveniently secured at the front of the fuselage quickly and conveniently.

Of course it will be understood that various modifications may be made in the construction and arrangement of parts without departing from the spirit of the invention as claimed.

I claim:

1. In a device of the class described, a pair of V-shaped side frames and a rectangular cross frame connecting the same at the back, said V-frames more separated at the back than at the front and an engine supporting frame projected inwardly between said V-frames and said back and extending fore and aft between the same.

2. In a device of the class described, a pair of V-shaped side frames and a rectangular cross frame connecting the same at the back, said V-frames more separated at the back than at the front and an engine supporting frame projected inwardly between said V-frames and said back and extending fore and aft between the same, and in combination with said device longeron sockets adapted to be secured at the corners of the same for attaching said device to the fuselage of an aeroplane.

In testimony whereof I hereunto affix my signature in the presence of two witnesses.

HUGH A. ROBINSON.

Witnesses:

LILLIAN DAVIDSON,
ANNA F. DUFFY
